BATTERY CABLE CLAMP COVER

Louis G. Franklin, Sioux City, Iowa

Application December 12, 1949, Serial No. 6,575

Term of patent 14 years

(Cl. D54—2)

To all whom it may concern:

Be it known that I, Louis G. Franklin, a citizen of the United States residing at Sioux City, in the county of Woodbury and State of Iowa, have invented a new, original, and ornamental Design for a Battery Cable Clamp Cover, of which the following is a specification, reference being had to the accompanying drawings, forming a part thereof, in which:

Figure 1 is a plan view of the battery cable clamp cover;

Figure 2 is a side elevation of Figure 1;

Figure 3 is an end elevation of Figure 1;

Figure 4 is a sectional view of the cable clamp cover taken substantially along the lines 4—4 of Figure 1; and

Figure 5 is a sectional view of the cable clamp

cover taken substantially along the lines 5—5 of Figure 2.

I claim:

The ornamental design for a battery cable clamp cover, as shown.

LOUIS G. FRANKLIN.
